UNITED STATES PATENT OFFICE.

WILLIAM GETHMANN, JOHN LOUIS GETHMANN, AND ADOLPH GETHMANN,
OF GLADBROOK, IOWA.

HALTER.

SPECIFICATION forming part of Letters Patent No. 434,182, dated August 12, 1890.

Application filed August 6, 1889. Serial No. 319,895. (No model.)

To all whom it may concern:

Be it known that we, WILLIAM GETHMANN, JOHN LOUIS GETHMANN, and ADOLPH GETHMANN, citizens of the United States, residing 5 at Gladbrook, in the county of Tama, State of Iowa, have invented certain new and useful Improvements in Halters, of which the following is a specification, reference being had therein to the accompanying drawings.

10 This invention has relation to halters.

The invention consists in the peculiarities of construction, the combination and arrangement of parts, and such other features as will be hereinafter more fully described, shown 15 in the drawings, and then particularly pointed out in the appended claims.

Referring to the drawings, Figure 1 represents a perspective view of our improved halter in its preferred form. Fig. 2 is a side elevation of a portion thereof, showing a slight modification. Fig. 3 is a perspective view of one of the clamps. Fig. 4 is a like view of the combined clamp and buckle. Fig. 5 is a side view of one of the holders.

20 Like letters indicate like parts throughout the several views.

In the drawings, A designates a strap, which in Fig. 1 is shown as forming but half of the nose-band, while in Fig. 2 it is shown as forming 25 the whole thereof.

In Fig. 1 the ends of the strap are shown as passed through a loop a and fastened by means of rivets or other suitable fastenings a'. These loops are formed integral with the 30 castings A', which are also formed with longitudinal apertures to receive the cord or rope B, and with a lateral arm A², formed upon its upper face with a depression a², beyond which is the lug or hook a³, and depending from this 35 arm near its outer end is the lug or pin a⁴. There are two of these castings, one at each 40 end of the strap when the strap forms but a half of the band, as shown in Fig. 1.

In the construction shown in Fig. 2, wherein 45 the strap forms the band entire, we employ a combined clamp and buckle, as shown more clearly detached in Fig. 4. It comprises in a single piece the shank C, of substantially the form shown in Fig. 4, provided with the jaws c, 50 the lug or pin c', and the rib c². This portion,

which constitutes the clamp, is designed to receive and hold one end of the rope D, as shown in Fig. 2, the pin c' embedding itself in the rope, the rib c² pressing against or embedding itself in the rope below the pin, and the jaws c being clasped around and firmly pressed into or against the rope. This forms a very secure means of holding the end of the rope. The ends of the jaws c are cut upon an incline in opposite directions, as shown 60 more clearly in Fig. 2, to provide for a better hold and to allow their more readily overlapping each other should they be used for clamping a smaller rope than that for which they were intended. The buckle part of this casting consists of the two loops C', separated by the vertical bar c³, which is formed with a lateral projection or pin c⁴. In practice the ends of the bands are passed in opposite directions through these two loops, with the pin c⁴ passing 65 through coincident holes in the two ends of the strap or band. (See Fig. 2.) One end of the strap should be provided with a plurality of holes, as shown in said Fig. 2, to provide 70 for adjustment thereof.

E is a strap, one end of which is passed through a loop f on the clamp F and securely fastened by means of rivets or other suitable fastenings f' and its other end adjustably connected with a smaller loop f of a light 75 clamp F. In the drawings we have shown a short link-strap G connected with said loop and carrying a buckle g, to which the end of the strap E is adjustably connected; but the form of connection between these parts may 80 be varied at pleasure. The clamps F are formed on the segments of a circle, as shown more clearly in Fig. 3, and have jaws f², adapted to be bent around and pressed firmly 85 against the rope, as shown in Fig. 1, a transverse rib f³ being provided to press into or against the rope to increase the clamp action 90 thereof.

When the strap A forms but half of the band, as shown in Fig. 1, the rope is attached 95 as follows: One end b thereof is placed beneath the arm A² of one of the clamps A' and the lug a⁴ thereof pressed into said rope, so as to hold it firmly. The rope is then bent around in the form of a half-circle, as shown 100

at b' in Fig. 1, thence up through the aperture in the casting A' , thence through the clamp F , from whence it is curved and passed downward through the loop h of the ring H , which latter loosely embraces the rope, as in Fig. 1, or the band, as in Fig. 2, (as the case may be,) and thence upward through the clamp F at the other end of the strap E , thence downward through the aperture in the other casting A' , thence into a half-circle parallel with the semicircular portion b' , and the end is then passed beneath the arm A^2 of the casting A' and has the pin a^4 thereof embedded therein. The two ends of the rope are held in place by means of wires b^2 wrapped around the rope and seated in the depressions a^2 of the arms A^2 , the hooks a^3 thereof preventing displacement of the rope-wires.

There are rings of malleable iron embracing the two strands of the rope, as shown in Fig. 1, and designed to be movable thereon, being held thereto by drawing together the ends or otherwise pressing the rings on the rope.

When the strap forms the entire band, as shown in Fig. 2, the arrangement of the rope is the same as that above described, and shown in Fig. 1, with the omission of the semicircular portions forming the half of the band in the form shown in Fig. 1, one end of the rope being attached to one of the clamps C , passed through one of the clamps F , thence through the loop h of the ring H , through the other clamp F , and secured to the other casting A' .

While both forms above described constitute a very complete and efficient halter, we

prefer that shown in Fig. 1, for the reason that it is so readily adjustable, for by simply loosening the rings I of the wrappings b^2 the ends of the rope may be drawn upon to readily adjust the rope to vary the dimensions and proportions of the parts to accommodate the halter to any sized animal. The adjustable rings I are also considered important.

What we claim as new is—

1. In a halter, the combination, with the band A and the castings A' , secured to the end thereof and formed with lateral arms, of the rope passed through openings in said castings and bent to form a continuation of the band, and fastenings, as b^2 , wrapped around the rope and the lateral arms of the castings and seated in a depression in said arms, substantially as shown and described.

2. In a halter, a clamp-casting provided with a loop and a lateral arm, said arm formed with a depression, a hook, and a depending pin, substantially as shown and described.

3. In a halter, the combination, with the throat and check straps, of a clamp F , formed with a loop f , a curved portion having jaws, and the transverse rib between said jaws and adapted to be adjusted upon the check-strap, substantially as described.

In testimony whereof we affix our signatures in presence of two witnesses.

WILLIAM GETHMANN.
J. LOUIS GETHMANN.
ADOLPH GETHMANN.
